UNITED STATES PATENT OFFICE

ALEXANDER I. FERRIER, OF DETROIT, MICHIGAN, ASSIGNOR TO PEN DESK SET COMPANY, OF CHICAGO, ILLINOIS, A CORPORATION OF ILLINOIS

FOUNTAIN PEN DESK SET

Application filed January 30, 1929. Serial No. 336,195.

This invention relates to improvements in supports for writing pens, and more particularly to that class of desk pen supports adapted for use in connection with capless 5 fountain pens, more commonly known as fountain pen desk sets.

It is a major purpose of the present invention to provide a fountain pen desk set support or set having universally adjustable 10 pen holding means whereby the pen may be maintained at any desired angle with respect to the base of the desk set.

It is a further object of the present invention to provide in a desk pen set of the class 15 described, improved means whereby ready adjustment of the pen supporting portion may be had, frictional means being employed to retain the said pen supporting portion in any desired adjusted position.

It is a still further object of the present invention to provide a desk pen set of the class set forth having improved adjustable frictional means adapted to retain the pen 25 supporting portion in any desired position, the said means being adjustable to vary the tension upon the bearing of the pen supporting portion at will, and being further adapted to compensate for wear thereon resultant through continued use.

It is a still further object of the invention to provide improved means within the pen supporting portion whereby the point of the pen may be maintained sealed and dust proof when the pen is not in use.

It is a further object of the present invention to provide a desk pen set or support of the class set forth which will be extremely ornamental in appearance, and durable as well as substantial in structure; which will be simple in operation; which may be conveniently assembled and which may be economically manufactured. Further objects of the invention will be hereinafter more fully set forth.

The accompanying drawings illustrate several desk pen sets or supports of preferred construction embodying the present invention which will be described in detail to enable others to understand and use the same, but the invention is not considered restricted

to the specific forms of construction which are shown in the drawings, and reference is therefore had to the claims for summaries of the essentials of the invention, and of the novel features of construction, and of the 55 novel combinations of parts for all of which protection is desired.

In the drawings:

Figure 1 is a top plan view of one form of desk pen set constructed in accordance with 60 the present invention, a portion of the pen proper being broken away.

Figure 2 is a longitudinal sectional view through the entire desk pen support, taken 65 on the line 2-2 of Figure 1.

Figure 3 is a transverse sectional view taken on the line 3-3 of Figure 2.

Figure 4 is an enlarged detail transverse sectional view through the pen supporting member, taken on the line 4-4 of Figure 2. 70

Figure 5 is a top plan view of a slightly modified form of desk pen set constructed in accordance with the present invention, a portion of the pen proper being broken away.

Figure 6 is a longitudinal sectional view 75 taken on the line 6-6 of Figure 5.

Figure 7 is a detail transverse sectional view taken on the line 7-7 of Figure 6.

Figures 8 and 9 are detail plan views of the 80 sealing washers detached.

Figure 10 is a longitudinal sectional view taken through a portion of a desk pen set illustrating a still further modified form of pen supporting member.

Figure 11 is a detail sectional view through 85 a portion of a pen supporting member illustrating a modified form of pen holding or sealing member therein.

Figure 12 is a detail elevational view of the 90 sealing member illustrated in Figure 11, detached.

Figure 13 is a view similar to Figure 11, illustrating a still further modified form of pen holding and sealing member.

Figure 14 is a detail elevational view of the 95 pen holding member illustrated in Figure 13, but detached.

Figure 15 is a longitudinal sectional view through a portion of a desk pen set illustrating a further slightly modified form of pen 100

supporting member somewhat similar to that shown in Figure 10.

Figure 16 is a longitudinal sectional view through a portion of a still further modified 5 form of desk pen set.

Figure 17 is a transverse sectional view through the desk pen set illustrated in Figure 16, taken on the line 17—17 thereof.

Figure 18 is a detail transverse sectional 10 view through a desk pen set similar to that shown in Figure 3, illustrating tapered conical extremities on the bearing member to which the pen supporting member is attached.

15 Figure 19 is a transverse sectional view similar to Figure 18 illustrating a modified form of adjustable frictional means for maintaining the bearing in adjusted position.

20 Figure 20 is a transverse sectional view illustrating a form of device similar to Figure 7, but illustrating a modified form of frictional means for maintaining the bearing in desired adjusted position.

25 Figure 21 is a transverse sectional view similar to Figure 20 but illustrating in combination therewith, a form of bearing having tapered conical extremities similar to that illustrated in Figures 18 and 19.

30 As shown in the drawings, the novel desk pen set comprises a base 1, which may be formed from any desired material, and which may be of any desired size and conformation and ornamental appearance. As shown in the form of the device illustrated in Figures 1 to 4 inclusive of the drawings, the base 35 may be rectangular in conformation, and is preferably hollow therebeneath as will be hereinafter more fully described. The base 1 is provided on its upper surface and adjacent the rear thereof, with a preferably centrally located circular aperture 1^a, adapted to receive a reduced portion 2^a formed upon a substantially hemi-spherically conformed housing 2 in which is pivotally mounted the 40 pen supporting member 3.

The base 1 is further provided with a second aperture 1^b through which is designed to project the neck 4^a of an ink containing receptacle 4 which may be mounted beneath the 45 base in any desired manner, preferably the aperture 1^b being centrally located and disposed adjacent the front of the base 1. Preferably a strap 4^b is provided to retain the ink receptacle against the under side of the top of the base, which may be recessed if desired as at 1^c. The strap may be secured in any desired manner, as by having the extremities thereof slotted or hooked for engagement with screws 1^d or the like threaded into bosses 50 60 1^e integrally formed within the hollow base. The ink receptacle may be provided with any suitably ornamental cap or cover 4^c, designed to protect the ink therein against dust or the like.

65 The housing 2 is designed to rotate upon

an axis perpendicular to the base, and as above described comprises an upper preferably circular portion and a reduced base portion which is adapted to fit snugly within the aperture 1^a in the base; the housing being provided with an enlarged shoulder or the like 2^b, the lower surface of which bears against the base of the desk pen set when the housing is in position, thus providing an additional bearing surface for the housing with respect to the base 1. 70 75

The housing 2 is provided with a meridional slot 2^c in which is guided the pen supporting member, the housing being of hollow interior conformation to provide a bearing 2^d 80 for a pivotal member 3^d to which the pen supporting member is secured, as will be herein-after more fully described.

The pen supporting member may be of any desired size and ornamental conformation, 85 comprising a body portion 3 provided with a slightly tapered bore or socket for the reception of the pen P, and having a reduced stem 3^a on its lower end designed to engage with the slot 2^c in the housing. Preferably this stem is formed with substantially flat opposite sides to provide snug bearing surfaces against the sides of the aforementioned slot. The opposite extremity of the pen supporting member may be slightly reduced and is exteriorly screw threaded for engagement with a similarly screw threaded ornamental cap or the like 3^b adapted for the retention of any desired form of sealing means for maintaining the pen within the supporting member in a sealed and dust proof condition. Preferably such sealing means comprises a pair of washers, or the like, 5, having their inner peripheries toothed or serrated as at 5^a. 90 95 100 105 110 115 120 125 130

From an examination of Figure 4 of the drawings, it will be obvious that the said washers are assembled in staggered relationship whereby the teeth on the one washer overlap the teeth on the other so that by this arrangement there is provided a novel structure which permits of the ready positioning of a pen within the supporting member and the ready withdrawal thereof, while when so positioned the point of the pen is maintained sealed and free from any foreign element as dust or the like.

The pen supporting member may be attached to the bearing member 3^d in any desired manner. Preferably the stem 3^a of the supporting member is recessed for the reception of a screw or the like 3^b adapted to be threaded into the bearing 3^d, preferably the relationship between the said stem and the bearing being such that the upper surface of the said stem merges into the upper surface of the aforesaid bearing.

Any desired means may be employed for retaining the pen supporting member in any desired adjusted position. One preferable

means comprises a frictional flat spring member 3^e secured to the under surface of the base of the desk set as by screws, etc. or the like 3^f. The spring member 3^e is provided adjacent the center thereof with an arcuate offset portion 3^g, which is adapted to bear against the member 3^d and thus serves to not only securely seat the member 3^d within its bearing but further provides frictional engagement therebetween thus assuring the pen supporting member remaining in any desired adjusted position. It will be noted that the extremities of the spring member project beyond the aperture 1^a, thereby preventing the displacement of the entire housing 2 and the pen supporting member therewith.

The operation of the entire desk set is extremely simple. Rotation of the housing will permit of any desired adjustment or variation between the pen holding member and the pen therewith, with respect to a vertical axis as between the housing and the base of the desk set; while the pen supporting member may be pivotally adjusted within the housing thus attaining any desired variation with respect to the horizontal axis.

In the form of the invention illustrated in Figures 5 to 9 inclusive of the drawings, the base 10 of the desk set has been shown as oval or elliptical in conformation, the base being provided with apertures 10^a and 10^b, similar to the apertures 1^a and 1^b, for the reception of the housing 12 and the ink receptacle 4. In this form of the invention, the ink receptacle 35 is retained in position identically as the receptacle in the form of the invention previously described, and accordingly it is believed needs no further discussion here.

The housing 12 comprises a upper hemispherical portion and a reduced portion 12^a adapted to be received within the aperture 10^a in the base and to rotate therein, the said reduced portion projecting beneath the base 10 and having the lower extremity thereof 45 screw threaded for engagement with a nut or the like 12^b designed to prevent displacement of the housing. The housing is further provided with an enlarged shoulder or the like 12^b, similar to the shoulder 2^b as above described and for an identical purpose. In the upper surface of the housing there is provided a meridional slot 12^c in which is guided the pen supporting member 3, the housing being of hollow interior conformation to provide a bearing 12^d and for a pivotal member 3^d to which the pen supporting member is designed to be attached.

The pen supporting member, as hereinbefore described, comprises a body portion 60 3 provided with a slightly tapered bore or socket for the reception of the pen P, and having a reduced stem 3^a on its lower end designed to engage within the slot 12^c in the housing. This stem is formed with substantially flat opposite sides to provide snug bear-

ing surfaces against the sides of the slot in the housing, the extremity of the stem being reduced and screw threaded as at 3^f for engagement with a similarly screw threaded recess within the bearing member 3^d.

The opposite extremity of the pen supporting member may be formed as has been previously described, with a threaded cap or the like 3^b adapted for the retention of the sealing means or washers 5 within the supporting member.

In this form of the invention a coil spring 12^f is provided for assuring the retention of the pen supporting member in any desired adjusted position. As shown in Figures 6 and 7 of the drawings, the said spring is positioned within the housing 12 and is adapted to bear against the member 3^d, thus serving to securely seat the said member within its bearing and providing frictional engagement therebetween. The spring 12^f is retained in position by means of a nut or the like 12^g, screw threaded within the reduced portion 12^a and obviously the tension of the spring against the member 12^d may be varied merely by adjustment of the nut; this being particularly desirable to compensate for any wear within the bearing resultant from continued use. It will be readily understood that the operation of this form of the invention is identical with that of the form thereof first herein described. The identical readiness and completeness of adjustability is had, and the essential elements of simplicity and convenience of assembly, manufacture and use being had.

In the form of the invention illustrated in Figure 10 of the drawings, the base 21 is provided with an aperture 21^a in which is positioned for rotation a member 22 provided with a reduced and flattened portion 22^a and which terminates at its upper extremity in a bearing member 22^b, similar in conformation and function to the bearing 3^d above described. A leaf spring or the like 22^c is suitably secured to the under surface of the member 22, and serves to retain the same in position for proper rotation. If desired the member 22 may be provided with a shoulder or the like 22^d to further assist in maintaining same positioned in the base.

The pen holding member 23 comprises a body portion provided with a slightly tapered socket for the reception of the pen P, and is further provided at both extremities with interiorly screw threaded sockets as will be hereinafter more fully described.

A split bearing member 23^a is provided for pivotal engagement with the bearing 22^b, the said member being slotted for engagement with the portion 22^a for adjustment therearound, the said member being reduced and also screw threaded for engagement with the lower end of the pen supporting member.

A socket 23^b is formed within the lower ex-

tremity of the member 23 and is adapted to house a coil spring or the like 23^d designed to bear against a bearing block 23^c which in turn bears against the bearing 22^b. The opposite 5 extremity of the pen supporting member is adapted for engagement with an externally screw threaded portion formed upon a cap member 23^e which serves to retain the sealing washers 5 therein in proper position. These 10 sealing washers are identical as illustrated and described in connection with the hereinbefore mentioned forms of the invention, and accordingly it is believed need no further discussion here.

15 Obviously this form of the invention comprises the positioning of the resilient means for insuring the stability of the pen supporting member within the said member.

In Figures 11 to 14 of the drawings, inclusive, there has been illustrated a portion of a pen supporting member 33 internally screw threaded for engagement with a cap or the like 33^a designed to secure in position resilient pen gripping members 33^b comprising 20 an outwardly directed annular shoulder or flange and downwardly depending spring fingers 33^c preferably formed integrally therewith.

As illustrated more specifically in Figure 33 of the drawings, each pen gripping member may include an integral ring like portion 33^d, or this portion may be omitted as shown in Figure 14. Any desired quantity of 35 spring fingers may be provided, in the two illustrations in the drawings (Figures 12 and 14) four and three of such fingers being illustrated respectively.

If desired, in connection with the pen gripping element above described, sealing washers 40 may be employed; or these washers may be omitted inasmuch as the pen may be designed to snugly fit within the member 33^b.

There has been illustrated in Figure 15 of the drawings a desk pen set including a base 45 21 provided with an aperture 21^a in which is positioned for rotation a member 22 provided with a reduced and squared portion 22^a which terminates at its upper extremity in a bearing member 22^b similar in conformation 50 and function to the bearing 22^b above described in connection with Figure 10 of the drawings.

The pen holding member 23 may be constructed identically, and the same combination of elements might be employed to insure proper frictional engagement as between the pen holding member and the bearing 22^b as has been illustrated and fully described in connection with Figure 10 of the drawings 55 and accordingly needs no further discussion here.

To retain the pen supporting member within the base, the lower extremity of the said member may be screw threaded as at 22^e for engagement with a locking nut 22^f.

The form of the invention illustrated in Figures 16 and 17 of the drawings includes a base 21 provided with an aperture 21^a in which is positioned for rotation a member 22 provided with a reduced and squared portion 22^a 70 which terminates at its upper extremity in a tubular bearing member 22^b. The lower extremity of the member 22 is screw threaded as above set forth at 22^e for engagement with the locking nut 22^f. It will be obvious from a comparison of this form of the invention with that illustrated in Figure 15, that the bearing portion proper may be slightly offset 75 from the vertical axis of the member 22.

The pen holding member 23 comprises a body portion provided with a slightly tapered bore or socket for the reception of the pen P and is formed with an interiorly screw threaded socket for the reception of the cap member 23^e which serves to retain the sealing washers 5 therein as has been previously described. The bottom extremity of the pen holding member is reduced and exteriorly screw threaded as at 23^f for engagement with a bearing member 23ⁱ adapted to surround 90 and have pivotal engagement with the bearing 22^b. Any desired frictional means might be employed to insure proper engagement as between the pen holding member and the bearing 22^b.

Preferably such means includes a leaf spring or the like 24 seated within the member 23ⁱ and having an arcuate offset portion 24^a adapted to engage against the bearing 22^b. The extremities of the member 24 are turned outwardly and are adapted to be engaged by the reduced portion 23^b of the pen holding member 23. It will be apparent that the engagement of the above described frictional means may be varied by rotation of the pen holding member 23 within the screw threaded socket in the bearing member 23ⁱ. The member 23ⁱ is slotted for engagement with the reduced and squared portion 22^a on the member 22; the operation of the device being identical as described in connection with Figure 10 of the drawings.

The form of the invention illustrated in Figure 18 of the drawings is similar to that disclosed in Figure 3 thereof. The base 1 is provided with an aperture 1^a adapted to receive a reduced portion 2^a formed upon a substantially dome shaped housing 2 of hollow interior conformation to provide a bearing 2^d for a member 3^d to which the pen supporting member is secured as has been previously described. In this form of the invention the bearing member 3^d is substantially tubular and includes conical extremities 3^x, the bearing 2^d being properly conformed to engage 110 therewith.

To provide for proper frictional relationship as between the bearing member 3^d and the housing 2, a flat spring member 3^e—offset as at 3^g—may be secured to the under 130

surface of the base as by screws or the like 3^c.

It has been found in practice that the tapered portions 3^x of the bearing member insure a more satisfactory frictional engagement within the housing whereby the pen holding member may be maintained in any desired adjusted position, and further more readily compensates for any wear resultant through continued use.

10. In Figure 19 of the drawings the base 1 is provided with an aperture 1^a adapted to receive the reduced portion 2^a on the dome shaped housing 2; the said reduced portion projecting downwardly through the base and being externally screw threaded for engagement of a locking nut 2^e. The housing 2 is of hollow interior conformation to provide a bearing 2^d for a substantially tubular bearing member 3^d to which the pen holding member 3 is attached. The bearing member 3^d includes conical extremities 3^x, the bearing 2^d being properly conformed to engage therewith. A frictional block 3^k conformed to snugly fit against the member 3^d is positioned 25 therebeneath and may be retaining in desired frictional engagement therewith by any desired frictional and adjustable means.

Preferably such means comprises an adjusting nut screw threaded within the lower reduced portion of the housing as indicated at 3ⁿ, a resilient spring like member 3^m being interposed between the said nut and the bearing block 3^k; thus combining with a tubular bearing having conical extremities, 35 frictional means variable or adjustable for maintaining the pen supporting member in any desired position.

In the forms of the invention illustrated in Figures 20 and 21 of the drawings, the 40 base 1 is provided with an aperture 1^a adapted to receive the reduced portion 2^a of a dome shaped housing 2, which is provided with an interior bearing 2^d for a pivotal member 3^d to which the pen supporting member 3 is designed to be attached. In Figure 20 of the drawings, the member 3^d is illustrated as tubular, while in Figure 21 the said member is provided with the above described conical tapered extremities 3^x. A leaf 50 spring 3° is secured to the bottom of the reduced portion of the housing 2, as by screws or the like, and is adapted to bear against the under surface of the base, thereby resiliently and frictionally securing the housing as against too free rotation. A bearing block or pad 3^k is adapted to be disposed against the under face of the bearing member 3^d.

A coil spring 3^p is disposed above the 60 spring 3° and bears against the pad 3^k insuring the proper frictional engagement of the bearing member 3^d within the bearing 2^d.

In the above described varied forms of the 65 invention preferred mountings for the pen supporting member have been illustrated

and described, whereby the desired and proper frictional engagement may be maintained between the required parts and whereby any wear thereon may be compensated for.

The desk sets thus described are highly ornamental in appearance, and are both extremely durable and substantial in structure. They are simple of operation, readily assembled, economical of manufacture and through the combination therewith of the ink receptacle may be as conveniently used with the ordinary forms of writing pens as with fountain pens.

The invention having thus been described, what is claimed is:—

1. A desk pen set comprising a base having an aperture therein, a substantially hemispherical housing slotted on its upper surface rotatably mounted in said aperture, the said housing being provided with an internal cylindrical recess, a pen supporting member mounted within the said housing, the said pen supporting member comprising a pen retaining portion, a stem portion adapted to travel within the aforesaid slot and a cylindrical bearing portion mounted within the recess in the housing, and resilient means carried by the housing adapted to frictionally engage the cylindrical bearing.

2. A desk pen set comprising a base having an aperture therein, a substantially hemispherical hollow housing slotted on its upper surface rotatably mounted in said aperture, the said housing being provided with a cylindrical recess, a pen supporting member mounted within the said housing, the pen supporting member comprising a pen retaining portion, a flattened stem portion adapted to travel within the aforesaid slot and a cylindrical portion journalled within the recess in the housing, and resilient means carried by the housing adapted to frictionally engage the cylindrical bearing.

3. A desk pen set comprising a base having an aperture therein, a substantially hemispherical hollow housing slotted on its upper surface and provided with a cylindrical recess rotatably mounted within the said aperture, a pen supporting member mounted within the said housing, the pen supporting member comprising a pen retaining portion, a reduced stem portion adapted to travel within the aforesaid slot, and a cylindrical bearing portion journalled within the recess in the housing, and resilient means carried by the housing adapted to bear against the cylindrical bearing on the pen supporting member and retain the same in any desired adjusted position.

4. A desk pen set comprising a base having an aperture therein, a substantially hemispherical hollow housing slotted on its upper surface and provided with a cylindrical recess, rotatably mounted within the said aperture, a pen supporting member pivotally

mounted within the said housing, the pen supporting member comprising a pen retaining portion, a reduced stem portion adapted to travel within the aforesaid slot, and a 5 cylindrical bearing portion journalled within the recess in the housing, and resilient means carried by the housing adapted to frictionally engage the cylindrical bearing whereby to retain the pen supporting member 10 in any desired adjusted position, and means for varying the tension of the said resilient means.

5. A desk pen set comprising a base having an aperture therein, a substantially hemi-spherical housing slotted on its upper surface and provided with an internal recess having a cylindrical bearing portion at the upper extremity thereof, rotatably mounted within the said aperture, a pen supporting member 15 pivotally mounted within the said housing, the pen supporting member including a pen retaining portion, a reduced stem portion adapted to travel within the aforesaid slot and engage the sides thereof and a cylindrical bearing portion journalled within the recess in the housing, resilient means carried by the housing adapted to frictionally engage the cylindrical bearing, and sealing means carried within the pen retaining portion where- 20 by the pen is maintained sealed.

6. A desk pen set comprising a base having an aperture therein, a substantially hollow hemi-spherical housing slotted on its upper surface and provided with a cylindrical 25 recess rotatably mounted within the said aperture, a pen supporting member journalled within the said housing adapted for pivotal movement relative thereto, the pen supporting member including a pen retaining portion, a reduced stem portion adapted to travel within the aforesaid slot, and a cylindrical bearing portion journalled within the recess in the housing, resilient means carried by the housing adapted to engage the cylindrical bearing whereby to retain the pen supporting member in adjusted position, and sealing means carried by the pen retaining portion adapted to maintain the pen sealed, said 40 means comprising a pair of toothed washers arranged in abutting relationship with the teeth thereof staggered.

7. A desk pen set comprising a base having an aperture therein, a substantially hollow hemi-spherical housing slotted on its upper surface and provided with a cylindrical 45 recess, rotatably mounted within the said aperture, a pen supporting member journalled within the said housing, the pen supporting member comprising a pen retaining portion, a reduced stem portion adapted to travel within the aforesaid slot and a cylindrical bearing portion journalled within the recess in the housing, resilient means carried by the housing adapted to frictionally engage the cylindrical bearing whereby the pen retain- 60

ing portion may be maintained in desired adjusted position, said means comprising a coil spring seated within the recess in the housing, means for varying the tension of the said spring on the cylindrical bearing, and 70 sealing means carried by the pen retaining portion whereby the pen may be maintained therein in sealed condition, the said means comprising a pair of abutting toothed washers, arranged so that the teeth of the one 75 washer is disposed in staggered relationship with respect to the teeth of the other washer.

8. In a recessed holder for pens, means for retaining a pen therein in sealed condition, said means comprising a pair of washers 80 toothed along their inner peripheries and arranged in abutting relationship, the said washers being so disposed that the teeth of one washer are staggered with respect to the teeth of the other washer.

9. In a desk pen set, in combination, a base having an aperture, a bearing member mounted within said aperture and adapted for yielding engagement with the base, a pen holding member mounted on said bearing member, the bearing member including a cylindrical portion having tapered conical extremities.

10. In a desk pen set, in combination, a base having an aperture, a bearing member mounted within said aperture and adapted for rotation under tension therein, and a pen holding member mounted on said bearing member, one of the members including a journal having an upper wall the outer portions of which are tapered adapted for engagement with a bearing formed upon the upper member, the said bearing being of cylindrical central conformation and having similarly tapered conical extremities.

11. In a desk pen set, in combination, a base having an aperture, a bearing member rotatably mounted within said aperture, a pen holding member mounted on said bearing member, one of the members including a bearing proper of substantially cylindrical conformation the outer extremities of which are frusto conical in conformation, and the other member being provided with a journal a portion of which is similar in conformation to the said bearing proper, and tensioning means for maintaining any desired adjusted relationship between the bearing member and the pen holding member.

12. In a desk pen set, in combination, a base having an aperture, a bearing member rotatably mounted within said aperture, a pen holding member pivotally mounted on said bearing member, one of the members including a bearing proper of cylindrical conformation the extremities of which are frusto conical in conformation and the other member including a journal for the said bearing a portion of which is similar in conformation thereto, and adjustable tensioning means for 130

maintaining any desired adjusted relationship between the bearing member and the pen holding member.

13. In a desk pen set, in combination, a base having an aperture, a bearing member rotatably mounted within said aperture, a pen holding member pivotally mounted on said bearing member, one of the members including a bearing proper of cylindrical conformation the extremities of which are frusto conical and the other member including a journal for the said bearing proper of similar conformation, and adjustable means for maintaining any desired relationship between the bearing member and the pen holding member, said means comprising a block adapted to bear against the bearing proper, the bearing surface of said block conforming to the tubular and conical surface thereof, and spring means for varying the pressure of the block.

14. In a desk set, a base, a receiving-receptacle, and means for mounting said receptacle on said base comprising a member rotatably mounted on said base, a member secured to said receptacle, said two members being connected together for swinging movement of said receptacle relative to said base, and a single spring means engaging said base and pressing said first member downwardly upon the base and tensioning the movements of said second member and said receptacle.

15. In a desk set, a base, a receiving-receptacle, and means for mounting said receptacle on said base comprising a member rotatably mounted on said base, a member secured to said receptacle, said two members being connected together for swinging movement of said receptacle relative to said base, spring means securing said base-mounted member to said base and also acting on said receptacle-mounted member for tensioning movements of said receptacle.

16. In a desk set, a base, a receiving-receptacle, and means for mounting said receptacle on said base comprising a member rotatably mounted on said base, a member secured to said receptacle, said two members being connected together for swinging movement of said receptacle relative to said base, and means for rotatably securing said base-mounted member to said base, said means also tensioning movement of said receptacle.

17. In a desk set, a base having an opening, a receptacle, a socket member having a part engaged in said base opening, a member on said receptacle engaged in said socket for swinging movement of said receptacle, a spring retainer carried by said socket member and engaging said base beneath said opening and also projecting into said socket member to engage said receptacle member for frictionally resisting its swinging movement.

18. In a desk set, a receptacle having one end open to receive the writing point end

of a writing instrument, a cap detachably mounted over the open end of said receptacle, said cap having a central opening through which the writing instrument is inserted, and means for retaining the writing instrument in said receptacle in sealed condition comprising a pair of superimposed washers between said cap and the part of said receptacle supporting it, said washers being formed of resilient material and having their inner peripheries serrated with the serrations of one washer staggered with respect to the serrations of the other.

19. In structure of the class described, a base, a receiving-receptacle having an opening to receive a fountain pen and means for mounting said receptacle for swinging movement on said base comprising a member mounted on said base, a swing-permitting connection between said receptacle and said member, and means carried by said receptacle between said swing connection and said receptacle opening for tensioning swinging movement of said receptacle and for holding the latter in any position to which it may be swung.

20. In structure of the class described, a base, a receiving receptacle having an opening to receive a fountain pen, and means for mounting said receptacle for swinging movement on said base comprising a member mounted on said base, a swing-permitting connection between said receptacle and said member, and spring means carried by said receptacle between said swinging connection and said receptacle opening for tensioning swinging movement of said receptacle and for holding the latter in any position to which it may be swung.

21. In a desk set, a base, a receiving-receptacle, and means for mounting said receptacle upon said base for swinging movement comprising a member fixed to said base, a member fixed to said receptacle, a swing-connection between said members, and tensioning means located between said receptacle and said second named member and opposing swinging movement of the latter.

22. In a desk set, a base, a receiving-receptacle, and means for mounting said receptacle upon said base for swinging movement comprising a member rotatably secured to said base, a member connected to said receptacle, a swing-connection between said members, tensioning means supported by said receptacle and opposing swinging movement of the latter, and separate tensioning means for opposing rotational movement of said base-mounted member.

In testimony whereof he affixes his signature.

ALEXANDER I. FERRIER.
